TUNING DEVICE

Application filed December 16, 1929. Serial No. 414,520.

This invention relates to tuning devices.

It is among the objects of the present invention to provide a novel and improved tuning device for radio receiving apparatus or the like, which includes novel means for indicating the position of the condenser or equivalent tuning unit, together with means for signaling when the tuning device is set to receive signals from a predetermined station.

10 A further object of the present invention is to provide a tuning device including a plurality of indicia having associated therewith illuminating means whereby movement of the tuning device will illuminate a selected indicia upon movement of the tuning apparatus to receive a predetermined signal corresponding with the indicia illuminated.

15 A further object of the present invention is to provide in a tuning device, means for indicating the frequency or wave length received without moving a calibrated dial. In the present instance the dial remains stationary and means are provided for causing a shadow of the pointer of the dial to indicate 20 the setting of the receiving apparatus.

25 A further object of the present invention is to provide in a device of the character described, novel construction, whereby the selected illumination of the indicia in response 30 to movement of the tuning apparatus, may be readily adjusted to suit various characteristics of the apparatus.

35 Other objects of the present invention include the novel and improved combination and interrelation of parts whereby the whole forms a novel, simple and improved structure well adapted to meet the demands of economic manufacture.

40 Further objects and features of the present invention will be apparent from a consideration of the following specification taken in conjunction with the accompanying drawings, in which

45 Figure 1 is a front elevation of a radio receiving cabinet embodying one form of the present invention;

Fig. 2 is a detail view of the cabinet with the name plate removed;

50 Fig. 3 is a longitudinal section through the cabinet illustrated in Fig. 1, and

Fig. 4 is a diagrammatic illustration of the wiring diagram used in connection with the form of the invention herein disclosed.

Referring more particularly to Fig. 1 of the drawings, it will be seen that the invention is disclosed in combination with a conventional radio receiving cabinet, which is generally indicated by the numeral 10. The central portion of the cabinet 10 is provided with a suitably designed area 11, adapted for the positioning of the tuning apparatus. In the form of the invention here shown, the area 11 is of round-top design with a straight bottom. Adjacent the edge of the area 11, there is provided a plurality of indicia 12, which are mounted within the control panel of the area 11, as indicated at 13 in Fig. 3. The indicia, as indicated in Fig. 3, are preferably formed upon suitable translucent or transparent members 14, which are secured in apertures of the panel 13, by the co-operation of an externally-threaded internal bushing 15 and a co-operating internally-threaded external bushing 16. Associated with the bushing 16 in a suitable manner, there is provided an illuminating lamp 17, the energization of which is adapted to be controlled with movement of the tuning unit, as will be hereinafter described. The indicia 12 are arranged in substantially semi-circular form radiating from the tuning unit control knob 18, which is arranged with the extending end of a control shaft 19.

55 Directly over the knob 18 in semi-circular formation, there is provided an arcuate aperture 20 in the panel 13. Suitably mounted in conjunction with the aperture 20, preferably on the inside of the panel and secured thereto by screws 21, there is provided a stationary calibrated translucent or transparent arcuate plate 22, the calibrations of which, as indicated in Fig. 2, are preferably in the form of frequency or wave length calibrations, the arrangement being such that the face of the plate 22 will indicate the wave length or frequency setting of the tuning unit.

60 As seen in Fig. 3, associated with the shaft 19, there is provided an arm 24 carried thereby for rotation therewith. The arm 24 is

provided with a lamp 25 or equivalent source of illumination, and further is provided with an indicating arm 26, which extends from the arm 24 in spaced relation thereto in front 5 of the lamp 25, the arrangement being such that when the lamp 25 is illuminated by suitable electrical association with the receiving circuit, a shadow is cast by the arm 26 upon the plate 22. Thus as the arm moves with the 10 tuning shaft 19, the shadow will move across the plate to indicate the setting of the tuning unit. By this construction, it will be seen that the calibrated dial or plate 22 remains stationary while the lamp and arm move in 15 unison behind the dial to provide for the indication on the dial of the setting of the tuning unit.

For controlling the selected energization of the lamps 17 to illuminate the members 14, 20 the arm 24 is provided with an extending contact arm 46, the upper extremity of which is provided with a contact element 27, and the panel 13 is provided with an arcuate aperture 28, within which a contact support 29 is provided, surrounding which movable contact 25 elements 30 are provided, one element 30 being provided for each of the illuminating means 17. As shown in Figure 2, the width of the contact elements 30 is preferably varied 30 in a proper sequence so as to be in conformation with the sharpness of tuning of the tuning unit. Thus if the tuning is very broad, the contact elements will be broad so that the indicia is illuminated over a relatively large 35 movement of the support 19. If, however, the tuning is particularly sharp, the contact elements 30 are relatively narrow, and thus the indicia illuminated is only at the precise point at which the circuit is tuned to the station indicated thereby.

As seen in Fig. 3, the elements 30 are secured to the member 29 by the tightening of securing screws 31, the arrangement being such that the screws 31 may be loosened and 45 the contact members 30 moved over their arcuate support 29, so that the energization of the associated lamp 17 is response to predetermined movement of the support 19 may be adjusted. For providing for ease of adjustment of the position of the contact members 30, the panel 13 is provided with a removable cover 32 secured to the panel, as by means of screws 33, the cover extending over the arcuate aperture 28, so that a removal of 55 the cover will render the adjustment of the contacts readily accessible.

In the preferred design of cabinet using the present invention, as shown in Fig. 1, the cover 32 is particularly adapted to be used as 60 a name-plate for the receiving device, it being understood that the cover may be provided with any desired ornamentation to conform with the ornamental effect of the cabinet.

By referring to Fig. 4, it will be noted that the arm 26 is electrically associated by a con-

ductor 35, with one side of a transformer or equivalent source of potential, indicated at 36. The opposite side of the source of potential is connected by a wire 37, which acts as a general conductor for all of the lamps 70 17. The opposite sides of the lamps are connected by conductors 38 to their respective contact members 30, as diagrammatically illustrated in this figure of the drawings. The arrangement is obviously such that as the 75 arm 24 moves with the contact support 19, the arm 26 and the contact 27 will move therewith, the contact passing over the contact elements 30, so that upon tuning of the device to a predetermined station, the contact 27 will become electrically associated with the selected element 30, and thus the lamp 17 over which the indicia corresponding to that station are positioned, will be illuminated. It will further be seen that by 80 removing the plate 32, the screws 31 may be loosened and the elements 30 moved over their arcuate support to vary the adjustment and thus to select the predetermined illumination of the lamps.

In some instances it may be desirable to provide for the simultaneous illumination of all the indicia 12. This is particularly desirable in connection with the display of the apparatus. For providing for simultaneous illumination of the indicia 12 by their associated lamps 17, a contacting band 40 of arcuate configuration is mounted within the panel and secured as at 43. The opposite end of the strip 40 is provided with an operating knob 41, which passes through a slot 42 in the panel, the arrangement being such that when the knob 41 is moved downwardly, in its slot, the strip moves out of its recess in the panel 13, to engage the upper connected ends of all the contact members. The strip 40 is associated by a conductor 44, with the conductor 45, thus upon contact thereof with the members 30, all the lamps 17 will be simultaneously energized.

From the foregoing it will readily be seen that the present invention provides a novel and improved tuning device, which includes with improved means for indicating on a calibrated plate the position of the tuning apparatus, means for illuminating suitable indicia in response to the predetermined movement of the tuning shaft. It will be understood that the present invention is not specifically confined to the definite structure of details herein presented, but that numerous changes, modifications, and the full use of equivalents may be resorted to in the formation of the invention without departure from the spirit or scope of the appended claims.

What is claimed is:

1. In a radio tuning device, a plurality of station indicators, an electric lamp for illuminating each of said indicators, a stationary contact for each of said lamps, a

movable tuning member, and a contact member movable with said tuning member for selectively engaging said contacts the stationary contacts having a width corresponding to the sharpness of tuning adjustment of said tuning member.

2. In a radio receiving apparatus, a panel, a plurality of translucent station indicators opening through said panel, an electric lamp for illuminating each of said indicators from the rear of said panel, a tuning member movably mounted in said panel, a support mounted on the rear side of said panel, a plurality of contacts adjustably mounted in spaced relation on said support, one in electrical connection with each of said lamps, a contact arm movable with said tuning member for selectively engaging said contacts, said panel having an opening in line with said support, and a removable closure for the said opening whereby the contacts will be accessible for adjustment through the latter when said closure is removed.

3. The device as set forth in claim 2, where-
25 in the said tuning member is constituted in a rotatable shaft, and the said support is arcuate in form to extend about said shaft to position the said contacts in proper co-
operative relation to the said contact arm.

30 4. In a radio receiving apparatus, a plurality of electric lamp station indicators, a movable tuning member, a plurality of spaced contacts at one side of said movable member, one in electrical connection with each 35 of said lamps, a contact arm movable with said member for selective engagement with said contacts to illuminate any one of said lamps, and a contact member common to all of said contacts and adapted to be moved 40 into direct engagement therewith for the simultaneous illumination of all of said lamps.

5. In a radio tuning device, a panel of an opaque material having a plurality of apertures therethrough disposed in an arched 45 arrangement, translucent members mounted in said apertures and each bearing a broad-
casting station designation, a lamp mounted at the rear of said panel one in line with each of the translucent members, contacts at 50 the rear of said panel and spaced in semi-
circular arrangement within the area defined by the arched arrangement of the said apertures, said contacts being in electrical connection with said lamps respectively and a 55 source of current supply, a tuning device having its shaft end rotatably journaled through said panel, and a contact arm carried by the tuning device shaft for wiping engagement with said contacts during the 60 operative movements of the shaft.

6. In a radio receiving apparatus, a plurality of translucent indicia, a plurality of lamps disposed at the rear of the translucent indicia respectively, a support, a plurality 65 of contact elements mounted on the support

and having electrical communication with the lamps respectively, a movable tuning member, a contact arm movable with said tuning member for selectively engaging said contact elements, and means for directly connecting the several contact elements with each other for lighting all the lamps at the same time.
